United States Patent Office.

ANTHONY ABEL, OF NEW YORK, N. Y., ASSIGNOR TO HIMSELF AND ADAM SCHWAB, OF SAME PLACE.

Letters Patent No. 100,487, dated March 8, 1870.

IMPROVED BARBER'S CHAIR.

The Schedule referred to in these Letters Patent and making part of the same.

To all whom it may concern:

Be it known that I, ANTHONY ABEL, of the city, county, and State of New York, have invented a new and useful Improvement in Barbers' Chairs; and I do hereby declare that the following is a full, clear, and exact description thereof, which will enable others skilled in the art to make and use the same, reference being had to the accompanying drawing forming part of this specification.

This invention relates to barbers' chairs, and consists in certain improvements thereon, which will be specified hereinafter.

In the accompanying drawings—

Figure 1 represents a chair with my adjusting device attached.

Figure 2 is a face view of the scroll gear-wheel.

Similar letters of reference indicate corresponding parts.

A is the back of the chair, the arms B of which are pivoted to the front legs, as seen in the drawing.

C is an upright bar or rack the upper end of which is hinged to the lower portion or edge of the back A.

D is a bracket which is supported from the staple E in the back edge of the seat F by means of the block G, which block is screwed into the lower arm of the bracket. There are slots in both arms of the bracket, through which the bar or rack C works up and down. One edge of this bar is serrated, or teeth or cogs are formed thereon, as seen in the drawing.

H is a conical gear-wheel, the thread of which engages with the teeth of the rack C.

This wheel is revolved by means of the crank I on

the shaft J, to the end of which shaft the wheel is attached.

K is a tube box attached to the back or upright portion of the bracket, by which box the shaft is supported.

The shaft J is placed at an angle of about forty-five degrees with the rack, so that the entire thread of the scroll or side of the cone is engaged with the teeth of the rack.

The pitch of the thread of the scroll and the teeth of the rack are made to correspond with each other, and the position of the cone is such that its side corresponds with the face or serrated edge of the rack. It will be seen that by this arrangement the back of the chair will be raised or lowered according as the crank is turned, and that unlike the ordinary rack and pinion this rack and scroll gear will remain stationary in any position without fastening of any kind. A scroll thread on a flat disk wheel and a cogged instead of a serrated rack may be employed, if desired.

Having thus described my invention,

I claim as new, and desire to secure by Letters Patent—

A barber's chair having the arms B pivoted to prolongations of the front legs and swinging thereon as a fulcrum, while the back A is raised or lowered by means of rack C and gear H, all arranged as specified.

The above specification of my invention signed by me this 10th day of January, 1870.
